H. WHEELER.
REGULATING VALVE.
APPLICATION FILED OCT. 27, 1910.

Patented Mar. 12, 1912.

UNITED STATES PATENT OFFICE,

HOLLAND WHEELER, OF LAWRENCE, KANSAS.

REGULATING-VALVE.

1,019,869.

Specification of Letters Patent.

Patented Mar. 12, 1912.

Application filed October 27, 1910. Serial No. 589,504.

To all whom it may concern:

Be it known that I, HOLLAND WHEELER, a citizen of the United States, residing at Lawrence, in the county of Douglas and 5 State of Kansas, have invented a new and useful Improvement in Regulating-Valves, of which the following is a specification.

My invention relates to improvements in cocks or valves which are attached to water 10 service pipes or other pipes to which it is applicable to regulate the flow of water therein,

I prefer to name the device "regulating valve."

15 The object of my invention is to produce a cock or valve which is simple, durable and inexpensive in construction, reliable in operation, and possessing such desirable features, as provision for a regulated or a full pipe 20 flow of water; provision for separating, storing and removing any deposit carried in the water supply which may prevent the discharge of a constant quantity through the regulating device, and for the last named 25 purposes, making all parts of the device accessible. I attain these objects by the mechanism illustrated in the accompanying drawings, in which—

Figure 1 is a vertical section of the body 30 and key of a cock similar to what is commonly known as "a straightway core cock," together with a section of the parts of my invention attached thereto, the center line of the same being a continuation of that of the key. Fig. 2 is a section of the same cock as described above in a plane through the center line of the body and at right angles to the key, and showing parts of a modified 35 form of my invention attached to the side of the body of the cock. Fig. 3 is a sectional elevation showing the handle of the key shown in Fig. 2 and showing parts of the cock with a modification of my invention 40 attached. Fig. 4 is a sectional elevation showing a modification of my invention. Fig. 5 is a sectional elevation of a part of 45 my invention showing a modification of same.

Similar reference numerals refer to similar parts throughout the several views.

The drawings are proportioned for a full sized one-half inch cock. The material used for the construction is preferably brass.

50 Referring to the drawings 1, 1 is the body of the cock or valve, the service pipe carry-

ing the water supply being attached to the right hand side of 1 by a screw joint.

2 is the rotatable key or plug of the cock.

3 is a full straightway opening in 2.

4 is an inlet hole in the side of 2 at right angles to 3 and opening into 3.

5 in Fig. 1 is an opening connecting with 3 and passes up through 2 opening into the parts above the key.

5' in Figs. 2, 3 and 4 is an opening in the side of the body 1, connecting with 3 when 65 2 is rotated and opening into the parts above the body and key.

6 in Fig. 1 is an extension of the top of the key.

6' as shown in Figs. 2, 3 and 4 is a boss or an extension of and an integral part of the side of the body 1, 1.

7 is a male screw on the top of 6 and 6'.

8 is a female screw in the top of 6 and 6'. 75

A hexagonal head on 6 shown in broken lines, is not numbered.

9 is a tube screwed into 8 in the top of 6 and 6' and opens into 5 and 5'.

10 is a hollow cylindrical reservoir attached to 6 and 6' by 7, it containing 9 which opens into it.

11 is a handle on 10, 11' is a handle on 2. 80 12 a hexagonal head on 10 shown in broken lines.

85

13 is a regulating plug, as shown in Figs. 1 and 2 it is screwed into 10, as shown in Fig. 3 it is screwed into 6' displacing 9, 9 and 10 being removed, it has a hole through 90 it the size of which determines the amount of the flow and is regulated for the pressure of the water supply.

13 is made of brass, hard rubber or other suitable material. 14 is a stop on 1. 15 is a stop on 6. These stops are only used on the 95 device as shown in Fig. 1.

16 as shown in Figs. 4 and 5 is a pet cock or valve which may be used instead of 13.

The operation of the device is as follows: 100 The key being in the first position as shown in the figures, water enters through 4, flows up in 3 and 5 or 5', thence through 9 into 10 and out at 13. In passing through 10 the deposit in the water is thrown down in it around 9. Where the quantity of deposit is 105 small and the service pipe may be trusted to retain it, the regulating device 13 or 16 is screwed into 8 and the reservoir 10 and pipe 9 omitted. Instead of the regulating plug 13, a pet cock, valve or similar device may 110

be used to regulate the flow. By turning the key by the handle one quarter turn to the left from the position shown in the drawings, it is in the second position, the full flow of water is turned through 1 and 3, the service pipe is cleared of deposit and the tank filled for testing without delay.

Referring to Fig. 1, by turning the key one half turn to the left from the position shown, it is in the third position, the water is shut off from all parts of the device, the stop 15 engages the stop 14 preventing 2 from turning more to the left. By turning the handle more to the left the reservoir 10 is unscrewed from 6 at the joint 7.

Referring to Figs. 2 and 3, the operation is the same as described above, except no stops are required to unscrew 10, and the key is turned by its handle 11.

Having unscrewed 10, all parts of the device are open and accessible for inspection, cleaning and repair; after which 10 may be again replaced by turning the key one revolution to the right, shutting off the water and engaging 14 and 15 to screw 10 in place. The key is then turned back to the position as shown in the drawing and the flow is again discharged through the regulating device.

The hexagonal heads shown on 6 and 10 by broken lines are for the use of wrenches when necessary.

Having described the construction and operation of my device, what I claim as my invention and desire to secure my Letters Patent is—

1. In a valve of the class described, the combination of a valve body having inlet and outlet chambers connected by a passage in which is fitted a rotatable key having a straightway opening, a port in said key at right angles to and connecting with the opening, opposite said port a stop section on the key, means for turning the key, a regulating plug or valve connected by a pas-

sage with the passage in the body of the valve and discharging out of it, all parts being so arranged that when said port of the key registers with the inlet chamber an operative passage will be formed to discharge the flow from the inlet chamber through the valve and out at the regulating plug or valve, or when the straightway opening in the key registers with the inlet and outlet chambers there will be a full straightway discharge through the valve, or the key being turned to cover the inlet chamber with the stop section all flow through the valve will be shut off, substantially as set forth.

2. In a valve of the class described, the combination of a valve body having inlet and outlet chambers connected by a passage in which is fitted a rotatable key having a straightway opening, a port in said key at right angles to and connecting with the opening, opposite said port a stop section on the key, means for turning the key, attached to said valve a vertical, cylindrical reservoir containing a vertical tube opening into it and connected by a passage with the passage in the body of the valve, a regulating plug or valve attached to said reservoir and discharging out of it, means for detaching the reservoir, all parts being so arranged that when the port of the key registers with the inlet chamber an operative passage will be formed to discharge the flow from the inlet chamber through the valve, the tube, the reservoir, and out at the regulating plug or valve, or when the straightway opening in the key registers with the inlet and outlet chambers there will be a full straightway discharge through the valve, or the key being turned to cover the inlet chamber with the stop section all flow through the valve will be shut off, substantially as set forth.

HOLLAND WHEELER.
